COMBINATION STEP STOOL AND SHOE SHINE CABINET

Earl K. Hansen, Chicago, Ill.

Application August 25, 1954, Serial No. 32,014

Term of patent 7 years

(Cl. D9—2)

Fig. 1 is a perspective view of a combination step stool and shoe shine cabinet showing my new design;

Fig. 2 is a perspective view of a combination step stool and shoe shine cabinet as viewed from the rear but with the cabinet of the stool in open position; and

Fig. 3 is a side elevational view of the same.

I claim:

The ornamental design for a combination step stool and shoe shine cabinet, as shown.
